CIGARETTE DISPENSING CASE

Pietro Seminara, Brooklyn, N. Y.

Application March 29, 1934, Serial No. 718,007

3 Claims. (Cl. 312—78)

This invention relates to certain new and useful improvements in cigarette dispensing cases.

The primary object of the invention is to provide a cigarette case wherein a case of ornamental design is provided with a tensioned false bottom upon which a plurality of cigarettes are perpendicularly supported and having means associated with the false bottom for holding it at its limit of downward movement against spring tension thereon and adapted for initial operation to permit functioning of tensioning devices associated with the false bottom for the automatic upward projection thereof and the projection of the upper ends of cigarettes above the upper end of the case.

A further object of the invention is to provide a cigarette dispensing case of the foregoing character wherein the tensioned false bottom for the support of cigarettes is normally retained in its lowered position by means of a system of links and levers with a pair of links normally occupying a position past dead center to retain the false bottom in its lowered position with the system of links and levers initially operated to move the pair of links to the other side of said dead center whereby the tensioning devices associated with the false bottom are operative for elevating the false bottom and projecting the cigarettes above the open upper end of the case.

With the above and other objects in view that will become apparent as the nature of the invention is better understood, the same consists in the novel form, combination and arrangement of parts hereinafter more fully described, shown in the accompanying drawing and claimed.

In the drawing:—

Figure 1 is a side elevational view of a cigarette dispensing device constructed in accordance with the present invention;

Figure 2 is a top plan view of the same showing the hinged cover;

Figure 3 is a top plan view with the hinged cover in open position and disclosing the cigarettes within the case;

Figure 4 is a vertical longitudinal sectional view with the cover in open position, the tensioned false bottom in its lower position and illustrating by dotted lines the link and lever devices for controlling operation of the false bottom;

Figure 5 is a longitudinal sectional view, similar to Figure 4, showing the tensioned false bottom in its elevated position with the cigarettes projected above the open upper end of the case; and

Figure 6 is a fragmentary bottom plan view of the case.

The cigarette dispensing case disclosed herein is of an ornamental character and comprises a body portion 10 mounted upon a base 11 carrying feet 12. The body portion 10 of the cigarette dispensing case comprises vertical side walls 13 and end walls 14 and 15, the open upper end of the case being closed by a cover 16 hinged as at 17 between the side walls 13 of the case adjacent their upper edges and at corresponding ends thereof. A tensioned arm 18 is secured as at 19 to the body portion 10 inwardly of the end wall 15 and is engaged with the hinge connection 17 for retaining the cover 16 in either open or closed position. An end partition wall 20 is set inwardly of the end wall 15 and spring arm 18.

The body portion 10 is of rectangular formation and is preferably of a width for supporting cigarettes perpendicularly disposed or supported on their ends as illustrated in Figs. 3 to 5, and said casing has a false bottom 21 vertically movable between the upper face 22 of the base 11 and the abutment shoulder 23 upon the end wall 14 and the lower end of the spring plate 19 as will be understood from an inspection of Figures 4 and 5. The base support 11 is provided with a centrally disposed slotted opening 24 extending vertically therethrough and an opening 25 adjacent each end of the slotted opening. The slotted opening 24 permits access to the false bottom 21, while each opening 25 houses a coil spring 26, the upper ends of which are engaged with the underside of the false bottom 21 while the lower ends are supported by plugs 27 slidably mounted in the lower ends of the openings 25 for placing the springs 26 under tension and said springs and plugs are retained in the openings 25 by means of a plate 28 set into a recess in the bottom face of the base support 11 to be flush therewith and so retained by means of the anchor screws 29. The coil springs 26 function to raise the false bottom 21 with the cigarettes C supported thereon as shown in Figure 4 for projecting the upper ends of the cigarettes above the open upper end 30 of the body portion 10 of the casing as illustrated by dotted lines in Figure 5. A pair of notched strips 30 are secured to the inner faces of the upper ends of the side walls 13 of the body portion for guiding the cigarettes in their upward movement and holding them separated from each other to facilitate removal.

To restrain the false bottom 21 from upward movement against the tension of the springs 26 and to hold the cigarettes C entirely confined 35

within the case, there is provided, as shown more clearly in Figures 4 and 5, a pair of links 31 and 32 pivoted together as at 33, the lower end of the link 32 being pivotally connected as at 34 to one side of the false bottom 21 intermediate its ends and in line with the slotted opening 24 which facilitates access to the pivot connection 34 while the upper free end of the link 31 is pivotally connected as at 35 to a cross strip 36 secured to a side wall 13 of the casing adjacent its upper end. A slide lever 37 extends through a side opening in the end wall 14 of the case and has its inner end pivotally attached to the connection 33 between the links 31 and 32 and the other end thereof projecting outwardly of the case provided with a bent finger grip 38 as shown more clearly in Figures 1 to 3. The links 31 and 32 are of a length when extended to permit movement of the pivot connection 33 beyond dead center as shown by dotted lines in Figure 4, this movement being limited by the finger grip 38 moving into engagement with the end wall 14 of the case and when the lever and links are so disposed, upward movement of the false bottom 21 under influence of the springs 26 is prevented.

In the use of the cigarette dispensing case, the cover 16 is first opened against the tension of the spring arm 18 and when opened is so retained by said spring arm as shown in Figures 4 and 5. The slide lever 37 is then operated to be moved outwardly of the body portion of the case and to dispose the pivot connection 33 between the links 31 and 32 at the opposite side of dead center, such positioning permitting functioning of the springs 26 for the raising of the false bottom 21 and the projection of the cigarettes C to the dotted line positions shown in Figure 5 and at which time they may be readily removed from the case.

From the above detailed description of the invention, it is believed that the construction and operation thereof will at once be apparent and while there is herein shown and described the preferred embodiment of the invention, it is nevertheless to be understood that minor changes may be made therein without departing from the spirit and scope of the invention as claimed.

I claim:—

1. In a cigarette dispensing case, a body and a supporting base, a false bottom vertically movable in the lower end of the body, spring members carried by the supporting base and engaged with the false bottom for normally influencing the same in an upward direction, and link and lever

devices disposed above the false bottom and including a pair of links respectively attached at their outer ends to the false bottom and body adjacent its upper end for holding the false bottom at its limit of downward movement and operative to release the false bottom to permit upward projection thereof by the spring members.

2. In a cigarette dispensing case, a body and a supporting base, a false bottom vertically movable in the lower end of the body, spring members carried by the supporting base and engaged with the false bottom for normally influencing the same in an upward direction, and link and lever devices disposed above the false bottom and body and associated therewith for holding the false bottom at its limit of downward movement and operative to release the false bottom to permit upward projection thereof by the spring members, the link and lever devices including a pair of pivotally connected links with the outer ends thereof respectively connected to the false bottom and upper end of the body, a slide lever extending through a side wall of the body and attached at its inner end to the pivotal connection between the links and a finger grip on the outer end of the slide lever for engagement with the body to limit upward movement of the slide lever.

3. In a cigarette dispensing case, a body and a supporting base, a false bottom vertically movable in the lower end of the body, spring members carried by the supporting base and engaged with the false bottom for normally influencing the same in an upward direction, and link and lever devices disposed above the false bottom and body and associated therewith for holding the false bottom at its limit of downward movement and operative to release the false bottom to permit upward projection thereof by the spring members, the link and lever devices including a pair of pivotally connected links with the outer ends thereof respectively connected to the false bottom and upper end of the body, a slide lever extending through a side wall of the body and attached at its inner end to the pivotal connection between the links, a finger grip on the outer end of the slide lever for engagement with the body to limit inward movement of the slide lever, and said lever and links being of lengths to permit movement of the pivotal connection between the links beyond a dead center for holding the false bottom in its lowered position with the latter acting to hold the lever and links in said position.

PIETRO SEMINARA.
